UNITED STATES PATENT OFFICE.

CLAYTON F. MACDONALD, OF ASHEVILLE, NORTH CAROLINA.

HYDRAULIC VACUUM CLEANING DEVICE.

Application filed November 4, 1926. Serial No. 146,220.

This invention relates to improvements in hydraulic vacuum cleaning devices, and has for its primary object to provide a device of this character that may be permanently installed within a building, and so constructed as to permit of the attachment of vacuum nozzles to the vacuum inlet pipe of the device so that carpets, articles of furniture, etc., etc., on the various floor levels of the building may be properly cleaned.

A further object is to provide a device of this character wherein a plurality of fluid jet nozzles are arranged in the vacuum chamber, all of which have communication with a single source of water supply, and complementary to each of which is an exhaust pipe for consequently multiplying the force of the vacuum within the chamber that would otherwise not be present in the case of but a single jet having a single exhaust pipe.

A further and most important object is to provide a vacuum cleaning device of this character wherein a supply of the vacuum producing fluid is injected into the vacuum chamber at the upper end thereof when the pressure of the fluid flowing into the chamber is relatively low for the purpose of effectively cleaning the interior of the chamber at the start and finish of the vacuum cleaning operation.

It is generally well known that hydraulic vacuum cleaning devices of this general character will in the course of time become so clogged with dust and dirt that the device will not operate by reason of the fact that the force of the suction effort is diminished to an impractical extent.

The invention further aims to provide means whereby the vacuum creating fluid and the dust and dirt drawn into the vacuum chamber by reason thereof may be effectively discharged into the sewerage system without disagreeable noises usually accompanying the exhaust of the fluid and without permitting the escape of the dust and dirt after being exhausted from the vacuum producing chamber.

A final salient object is to provide a vacuum cleaning device of this character that is of extremely simple construction, inexpensive of installation, and highly effective in its operation.

Other objects will become apparent as the nature of the invention is better understood.

the same comprising the novel form, combination, and arrangement of parts herein-after more fully described, shown in the accompanying drawing and claimed.

In the drawings wherein like reference characters indicate corresponding parts throughout the several views:

Figure 1 is a fragmentary vertical section through a building having installed therein a vacuum cleaning device constructed in accordance with the present invention.

Figure 2 is a view partly in side elevation, and partly in section of the device, per se.

Figure 3 is a detail vertical section taken at right angles through the device as disclosed in Figure 2, and

Figure 4 is a transverse section taken substantially upon the line 4—4 of Figure 3.

Now having particular reference to the drawings wherein there is disclosed the most practical embodiment of the invention with which I am at this time familiar, 5 designates a metallic vacuum chamber preferably of square shape in cross section as indicated in Figure 4, the outer side wall of which is provided with a large hand opening 6 within which is arranged and rigidly secured a closure plate 7 having a normally plugged opening 8 therein. The lower end of the vacuum chamber 5 is of tapering formation 85 as clearly disclosed in Figures 1 and 3, and the end thereof terminates into a pair of branch pipes 9—9 between which at the upper ends thereof is a pyramidal spacing block 10 serving to guide the vacuum producing fluid together with the dust and dirt into said branch pipes 9—9 and for preventing the accumulation of the dust and dirt therebetween.

The top wall of the vacuum chamber 5 is provided with a threaded opening 11 within which is arranged one end of an elongated vertical dirt and dust inlet pipe 12 that is extended vertically through the floor level of the building A in Figure 1, 100 and equipped at each floor level with a vacuum hose connection B, it being obvious from a consideration of Figure 1 that the vacuum chamber of the device is disposed within the cellar of the building.

The side wall of the vacuum chamber 5 opposite the hand opening 6 is formed with an opening 13 within which is mounted the inlet end of a Y-pipe 14, the branches of which terminate in a depending manner within the

center of the chamber, and in exact centered relation with respect to the exhaust branches 9-9 of said vacuum chamber. Within the exhaust ends of the branches are jet nozzles 15-15, the bores of which are of tapering formation so as to provide restricted discharge openings at the outer ends thereof, see Figure 3.

In communication with the branch pipe 14 at the inlet end thereof, and at the outer side of the vacuum chamber 5 is a short pipe fitting 16 in communication with the outer end of which is a fluid inlet pipe 17 in communication with a source of steam compressed air or water supply, preferably the building water supply and within which pipe is located a conventional globe valve 18, see Figure 1.

Associated with the core of this valve is an elongated vertical rod 19 that extends through the floor levels of the building A, and is equipped at each floor level with an operating handle 20 so that the valve may be turned on or off at any floor level.

The top side of the fitting 16 is formed with an opening 18' across the center of which is a ball valve supporting pin 19'. Arranged upon the top side of this fitting 16 and having communication with the opening 18' therein is a small fluid chamber 20 upon the upper end of which is a cap head 21 threaded into which is one end of an elbow pipe 22, the opposite end of which has communication with the interior of the

vacuum chamber 5 at the upper end thereof. Arranged within this fluid chamber is a ball valve 23 that under zero or low water pressure will rest upon the pin 19 as disclosed by the full lines in Figure 3. Obviously, as the valve is turned on to permit the introduction of the fluid into the vacuum chamber through the jet nozzles 15-15, the pressure will be relatively low and consequently the ball 23 will not be raised to the

dotted line position in Figure 3 which would close the fluid passage through the elbow pipe 22, thus allowing a certain amount of the fluid to pass through the elbow pipe and enter the vacuum chamber 5 at the upper end thereof for thoroughly cleaning the interior of the chamber at the initial operation of the device. This is also true at the end of the operation by reason of the fact that as the globe valve 18 is operated for

cutting off the supply of fluid, the pressure will be reduced at the end of the closing operation, again letting in a certain amount of the fluid for cleaning the interior of the vacuum chamber during the last stages of operation of the device. As soon as the pressure of the fluid passing into the vacuum chamber has reached a certain degree, the ball valve 23 will be automatically raised as indicated by the dotted lines in Figure 3 for closing the fluid by-pass to the interior

of the chamber so that the full force of the pressure will be employed in creating the vacuum within the chamber.

Attached to the branch pipes 9-9 of the vacuum chamber and this preferably by reason of a two-part clamp 24 are relatively elongated exhaust pipes 25-25. By providing pipes of relatively great length, for example, four to seven feet, the fluid exhausting from the jet nozzles 15-15 will encounter the entire inner surface of these pipes effecting pistons passing therethrough and by the long stroke of the columns of water between the inlet and outlets of said pipes a great pull or vacuum force will be provided for the vacuum chamber 5. Obviously, by reason of the two exhaust pipes 25-25 together with their complementary jet nozzles 15-15 a double force of the vacuum will be secured even though a single supply of fluid under pressure is present.

The lower ends of the exhaust pipes 25 are arranged within a tank 26 from which leads, a discharge pipe 27 in communication with the sewerage system. This pipe 27 is in communication with the tank above the bottom wall thereof so as to maintain a cushion of water within the tank as clearly disclosed in Figures 2 and 3.

In addition to the connection B within the cellar of the building the plug opening 8 in the insert plate 7 of the vacuum chamber 5 is provided in order that the flue of the furnace C may be conveniently cleaned.

It will thus be seen that I have provided a highly novel, simple and efficient hydraulic vacuum cleaning device that is well adapted for all the purposes heretofore designated, and even though I have herein shown and described the invention as consisting of certain detail structural elements it is nevertheless to be understood that some changes may be made therein without affecting the spirit and scope of the appended claims.

Having thus described the invention, what I claim as new and desire to secure by Letters Patent is:

1. In a vacuum cleaning device of the character described, a vacuum chamber having a suction inlet at one end, and a pair of exhaust pipes at its opposite end, a double jet nozzle arranged within the vacuum chamber each of said nozzles being centered above the respective exhaust pipes of the vacuum chamber, a common fluid pressure inlet for said jet nozzle, and means automatically operable for introducing a charge of the fluid into the chamber above the nozzle during low pressures of the fluid, said means being inoperative when the pressure of the fluid reaches a predetermined degree.

2. In a hydraulic vacuum cleaning device of the class described, a vacuum chamber having a waste inlet in the top thereof,

and a suction inlet in one side thereof adjacent the top, a fluid exhaust at the lower end of the vacuum chamber, a fluid nozzle fitted at one end in said suction inlet, said 5 nozzle being arranged within the vacuum chamber and having its discharge end disposed directly above said aforementioned exhaust, a fluid supply pipe communicating with said nozzle, means whereby a certain 10 quantity of the fluid will enter the upper portion of the vacuum chamber above said nozzle to clean the wall thereof when the pressure of the fluid reaches a predetermined point, said means comprising a fitting 15 interposed between the fluid supply pipe and said nozzle, a fluid receiving chamber arranged on the top of the fitting and communicating with the bore thereof, a pipe affording communication between the top 20 of said chamber and the extreme upper portion of the vacuum chamber, and a normally open valve arranged within the fluid chamber on said fitting.

3. In a hydraulic vacuum cleaning device of the class described, a vacuum chamber having a suction inlet at one end, and a fluid exhaust at its opposite end, a fluid jet nozzle arranged within the chamber in such a manner that the fluid will be caused 25 to discharge through the exhaust of the chamber for creating a vacuum therein, a fluid supply pipe communicating with the jet nozzle, means automatically operable under low pressures of the fluid for introducing fluid into the chamber above the jet 30 nozzle for cleaning the interior of the chamber, said means consisting of a branch pipe in communication at one end with the source of fluid supply and at its opposite 35 end with the interior of the vacuum chamber, and a normally open valve operable to closed position when a predetermined difference of pressure exists between the branch pipe and the fluid supply pipe.

4. In a hydraulic vacuum cleaning device, a vacuum chamber having a suction inlet at one end, and a pair of exhaust nozzles at its opposite end, elongated discharge pipes in communication with said exhaust 40 nozzles, a pair of fluid ejecting jet nozzles arranged within the chamber and being

centered above the exhaust pipe, a common fluid supply pipe for both of said jet nozzles, and means whereby a certain quantity of the fluid may be introduced into the 55 chamber above the jet nozzles for cleaning said chamber, said means comprising a branch pipe extending between the supply pipe and the upper portion of the vacuum chamber, and a normally open valve in the 60 branch pipe operable to a closed position when a predetermined difference of pressure exists between the branch pipe and the fluid supply pipe.

5. In a hydraulic vacuum cleaning device 65 of the class described, a vacuum chamber having a suction inlet at one end, and a fluid exhaust at its opposite end, a fluid jet nozzle arranged within the chamber in such a manner that the fluid will be caused to 70 discharge through the exhaust of the chamber for creating a vacuum therein, a fluid supply pipe communicating with the jet nozzle, a by-pass structure between the supply pipe and the top portion of the vacuum 75 chamber, and a pressure controlled valve arranged in the by-pass for permitting a supply of the fluid to enter the top of the chamber only when the fluid supply pressure is exceedingly low.

6. In a hydraulic vacuum cleaning device of the class described, a vacuum chamber having a waste inlet in the top thereof, and a suction inlet in one side thereof adjacent the top, a fluid exhaust at the lower 80 end of the vacuum chamber, a fluid nozzle fitted at one end in the suction inlet, said nozzle being arranged within the vacuum chamber and having its discharge end disposed directly above the aforementioned exhaust, a fluid supply pipe communicating with said nozzle, a by-pass structure affording communication between the supply pipe and the top of the vacuum chamber, and a pressure controlled vertically mov- 85 able valve arranged in the by-pass structure for permitting a quantity of the fluid to enter the top of the vacuum chamber to clean the walls thereof only when the fluid supply pressure is exceedingly low.

In testimony whereof I affix my signature.
CLAYTON F. MACDONALD.
